UNITED STATES PATENT OFFICE.

ORA NORCROSS TURNER, OF TEMPLETON, MASSACHUSETTS, ASSIGNOR TO BAY STATE METAL WHEEL COMPANY, OF EAST TEMPLETON, MASSACHUSETTS, A CORPORATION OF MASSACHUSETTS.

FOLDING CARRIAGE.

No. 899,851.

Specification of Letters Patent.

Patented Sept. 29, 1908.

Application filed December 19, 1907. Serial No. 407,164.

To all whom it may concern:

Be it known that I, ORA NORCROSS TURNER, of Templeton, in the county of Worcester and State of Massachusetts, have invented certain new and useful Improvements in Folding Carriages, of which the following is a specification.

This invention relates to baby carriages or perambulators so-called, adapted to be folded into compact form when not in use, and particularly to that class of folding perambulators in which two wheel-carrying frames are hinged to the seat-supporting frame, each wheel-carrying frame extending lengthwise of the carriage, and being adapted to be retracted by swinging inwardly under the seat frame, and to be projected outwardly from under the seat frame into position for use.

20. The invention has for its object to provide improved means for locking the wheel-carrying frames when they are in their projected or operative positions, said locking means being made operative and inoperative by the same mechanism which projects and retracts the wheels.

The invention also has for its object to provide certain improvements relating to the wheel-retracting and projecting mechanism 30 and to other structural features of the carriage.

The invention consists in the improvements which I will now proceed to describe and claim.

35. Of the accompanying drawings, forming a part of this specification, Figure 1 represents a side elevation of a carriage embodying my invention in its extended position ready for use. Fig. 2 represents a rear elevation of the carriage adjusted as shown in Fig. 1, portions of the upper works of the carriage being broken away. Fig. 3 represents a view similar to Fig. 1, showing the carriage partially folded. Fig. 4 represents a view similar to Fig. 2, showing the carriage in the condition represented in Fig. 3. Fig. 5 represents a top plan view of the carriage with the seat and other parts of the upper works removed to show the seat frame and the parts below 50 the same. Fig. 6 represents a rear end elevation showing the carriage folded. Fig. 7 represents a fragmentary view illustrating by full and dotted lines, different adjustments of the carriage.

The same letters of reference indicate the 55 same parts in all the figures.

The seat-supporting frame of my improved carriage is preferably composed of longitudinal side bars 12 and transverse end bars 13, suitably riveted together to form a 60 rectangular open frame, the side bars 12 being bent downwardly at their ends to form ears 14, to which the wheel frames are connected by pivot bolts 16. Each wheel frame is preferably composed of two parallel bars 65 17 having bent ends 18 which are overlapped and riveted together, the whole forming an open frame between the side bars of which the upper portions of the wheels 19 are located. This construction of the wheel 70 frames is best shown in Fig. 3.

Each of the side bars 17 is provided with downwardly-projecting hangers 20, to which are affixed short axles 21 on which the hubs of the wheels are journaled. The bent ends 75 18 of the outer bars of the wheel frames are extended inwardly far enough to form ears to engage the pivot bolts 16, as indicated by dotted lines in Figs. 2 and 4. The described construction permits the wheel frames to 80 swing inwardly under the seat frame, as indicated in Figs. 4 and 6, to retract the wheels and fold the carriage. When the wheel frames are projected to make the carriage operative, as shown in Figs. 1 and 2, the 85 end bars 18 of the wheel frames bear against inwardly-bent stop ears 22 formed on cross bars 23, which are riveted to the downwardly-bent ends 14 of the side bars of the seat frame. The ears 22 limit the outward swinging movements of the wheel frames, and insure stability when the wheels are fully projected. The end bars 13 of the seat frame are bent upwardly at their ends to form ears, the front cross bar having relatively short 90 ears 24, while the rear end bar has longer ears 25. To the ears 25 are pivoted at 26 the side bars 27 of the handle, the latter being preferably composed of a tubular rod or bar bent into U form, the end portions of the bar forming the side bars 27, while the central portion forms a connecting cross bar or neck 28 at the upper end of the handle.

29 represents a seat to the ends of which are attached rearwardly-projecting arms 30, 105 and downwardly-projecting shorter arms 31, said arms 30 and 31 being preferably formed in one piece, which is screwed to the ends of

the seat. The arms 30 are pivoted at 32 to the side bars of the handle, and the arms 31 are pivoted at 33 to levers 34, which in turn are pivoted at 35 to ears affixed to the side bars 12 of the seat frame. The longer upper arms of the levers 34 are connected with the side bars of the handle by links or arms 36.

37 represents a dasher frame having at its ends downwardly-projecting ears 38, which are pivoted at 39 to the ears 24 on the front end bars of the seat frame. The ears 38 are connected by rods 40 with the shorter lower arms of the levers 34.

The handle is locked in its operative position, shown in Figs. 1 and 2, by means of toggle links 41 42, which are jointed together at 43, one of said links being jointed to the handle, and the other to the arm 36. When the links are in alinement with each other, as shown in Fig. 1, they constitute a brace or strut, which locks the handle, the arms 36, levers 34, rods 40 and dasher 37 in their operative positions, and prevent the folding of the carriage. When the links are thrown out of alinement with each other, the handle is free to swing forward and thus cause the folding of the parts connected therewith, as indicated in Fig. 3. The forward swinging of the handle and of the levers 34 causes the seat 29 to move downwardly toward the seat frame, the dasher at the same time swinging backwardly toward the seat. When the handle reaches the extreme of its forward swinging movement, the above-described parts connected therewith, are compactly folded, as indicated in Fig. 6.

The described mechanism for folding the carriage, including the handle 27, has provisions for retracting the wheels while the carriage is being folded, and for projecting the wheels when the carriage is being expanded, and additional provisions for locking or firmly bracing the wheel frames when they are projected, so that the wheels cannot accidentally collapse, and, in fact, cannot be swung inwardly until the handle is swung forward. The said provisions for bracing or locking the wheel frames is one of the most important features of my invention. As here shown, that part of my invention which relates to the swinging and locking of the wheel frames, is embodied in the construction next described.

44 44 represent U-shaped links, the ends 55 45 of which are pivoted at 46 to the rear end portions of the side bars of the wheel frames. To the links or pivoted ears 44 are pivoted at 47 the lower ends of connecting rods 48, the upper ends of which are pivoted at 49 to the side bars 27 of the handle. The links or ears 44 and connecting rods 48 constitute a double-jointed connection between the handle and the wheel frames, which is adapted, when the handle is swung forwardly, to swing the wheel frames inwardly under the

seat frame. When the handle is in its operative position, the connecting rods 48 are at the rear of the handle pivots 26, as shown in Fig. 1. As the handle swings forward, the connecting rods are moved across the pivots 26, and as soon as the handle is inclined toward the front end of the carriage, the connecting rods 48 commence to move downwardly, and thus exert pressure on the wheel frames through the links 44, tending to swing the wheel frames inwardly, the links swinging on their pivotal connection 47 with the connecting rods. The described parts are so formed and arranged that one wheel frame is swung slightly in advance of the other, so that the wheels do not interfere with each other in the operation of folding and unfolding the carriage. When the handle is swung backwardly toward its operative position, the connecting rods 48 and links 44 exert an outward pull on the wheel frames until the wheels are projected.

The provision for bracing or locking the wheel frames, which constitutes a very important part of my invention, comprises struts connected at their ends with the wheel frames, and extending across the space between the same, said struts being adapted to be extended to brace or lock the wheel frames, and contracted to release the same, and permit their retraction. These struts, which are best shown in Figs. 2 and 4, are in this embodiment of my invention, composed of a central toggle link 50 and two end toggle links 51, which are jointed at 52 to the central link 50. The end links 51 are jointed at 53 to ears affixed to the hangers 20 of the wheel frames. The end portions of the central link 50 are curved upwardly, and provided with stop studs 54, which bear on the upper edges of the end links 51 when the toggle is extended, as shown in Fig. 2. When the toggle is in this position, it constitutes a rigid strut, which prevents movement of the wheel frames inwardly toward each other. When the central link 50 is raised, it breaks or contracts the toggle, as indicated in Fig. 4, so that the wheel frames are free to swing inwardly toward each other. Two of the described toggles are provided in this instance, one connecting the hangers in which the front wheels are journaled, and the other connecting the hangers which carry the rear wheels. The central links 50 of the two toggles are connected by a longitudinal rod 55. 120

The means next described are provided for breaking and extending the toggle struts, or, in other words, raising the central links of the struts, as shown in Fig. 4, and depressing the same, as shown in Fig. 2. 125

56 represents a cross bar having bent ends 57, which are engaged by the handle pivots 26, and are adapted to swing on the latter. The cross bar 56 is connected by a link 58 with a lifting lever 59, one end of which is 130

pivoted at 60 to an ear 61 affixed to the rear end bar of the seat frame. The other end of the lever 59 is bent to form an ear 62, which is perforated to receive the rod 55 connecting 5 the two toggle struts. The ears 57 at the ends of the cross bar 56 are connected by links 63 with the arms 30.

The operation of the described toggle-breaking and extending mechanism is clearly 10 illustrated by full and dotted lines in Fig. 7, by reference to which it will be seen that when the handle is in its operative position, the cross bar 56 is depressed toward the seat frame, and acts through the link 58 to correspondingly depress the lever 59, and through 15 the connecting rod 55, the central links 50 of the toggle struts. When the handle is swung forward, as indicated by dotted lines in Fig. 7, the cross bar 56 is raised from the seat 20 frame, and the lever 59 is swung upwardly, thus raising the connecting rod 55 and the central links 50 of the toggle struts, and breaking the toggle, as indicated in Fig. 4. When the handle is swung backwardly to its 25 operative position, the cross bar 56, the lever 59, the connecting rod 55 and the central toggle links 50 are again depressed, the toggles being thus extended, and caused to lock the wheel frames. The described locking de- 30 vices or toggle struts are contracted or broken to release the wheel frames just before the latter are swung inwardly to retract the wheels, and are projected to lock the wheel frames just after the latter have been 35 swung outwardly to their fullest extent to project the wheels.

The locking devices or toggle struts are separate from the mechanism which causes the parts of the carriage, including the wheel- 40 carrying frames to fold, in that said locking devices or toggle struts are not parts of the same mechanism which does the folding and unfolding. While the parts themselves, that is the locking devices or struts, are separate 45 from or independent of the folding mechanism in structure, yet there are connections including the rod 55 and lever 59, whereby the locking device is made alternately opera- 50 tive and inoperative through the operation of the folding mechanism.

70 represents a back which is hinged at 71 to ears on the seat, and is supported in its operative position by a bent rod 72 pivoted at 73 to the arms 36, and engaged with guide 55 rods 74 on the rear side of the back.

75 represents a collapsible pocket of flexible material, attached at its rear edge to the front end of the seat, and at its front edge to the dasher 37. The bottom 76 of the pocket 60 constitutes a foot rest when the occupant of the carriage is in a sitting position. The flexibility of the pocket 75 is such that it is collapsed, as shown in Fig. 3, by the folding of the carriage.

65 I believe myself to be the first to provide

in a folding carriage having wheel-carrying frames which are pivoted to the seat frame, and adapted to swing laterally to project and retract the wheels, a folding mechanism for swinging said frames to retract and project 70 the wheels, a device for locking and releasing the wheel frames, and connections between the folding mechanism and locking device whereby the latter is automatically actuated through the operation of the folding mechanism, the arrangement being such that when the folding mechanism is actuated to retract the wheels and fold the carriage, the locking device is first unlocked to release the wheels, and the latter are then swung inwardly, and 80 when the reverse action takes place, the wheels are first swung outwardly, and the locking device is then made operative to lock the wheels.

It is obvious that my invention may be 85 embodied in a carriage having one locking device or strut, instead of two, as here shown, although two locking devices are obviously preferable. I do not therefore limit myself to the described details of mechanism for ac- 90 complishing this result, as the same may be variously modified without departing from the spirit of my invention.

I claim:

1. In a folding carriage, the combination 95 of a seat frame, laterally-swinging wheel-carrying frames pivoted thereto, folding mechanism for swinging said frames to retract and project the wheels, a jointed locking device extending across the space be- 100 tween the wheel carrying frames for locking and releasing the same, the folding mechanism being separate from the locking device, and connections between the folding mech- 105 anism and locking device whereby the latter is made alternately operative and inoperative through the operation of the folding mechanism.

2. In a folding carriage, the combination 110 of a seat frame, laterally-swinging wheel- carrying frames pivoted thereto, folding mechanism for swinging said frames to retract and project the wheels, a strut connect- 115 ing the wheel frames and adapted to be lengthened and shortened to lock and release the wheel frames, the strut being separate from the folding mechanism, and connections between said folding mechanism and strut whereby the latter is automatically short- 120 ened and lengthened by the operation of the folding mechanism.

3. In a folding carriage, the combination 125 of a seat frame, laterally-swinging wheel- carrying frames pivoted thereto, folding mechanism for swinging said frames to retract and project the wheels, a toggle strut connect- 130 ing the wheel frames, the strut being separate from the folding mechanism, and connections between said toggle and the folding mechanism, whereby the toggle is

alternately broken and extended by the operation of the folding mechanism.

4. In a folding carriage, the combination of a seat frame, laterally-swinging wheel-carrying frames pivoted thereto, folding mechanism for swinging said frames to retract and project the wheels, a toggle strut connecting the wheel frames, and comprising a central link and two end links jointed to the central link and to the wheel frames, and connections between the central link and the folding mechanism adapted to raise and depress the central link to break and extend the toggle when the folding mechanism is operated to retract and project the wheel frames.

5. In a folding carriage, the combination of a seat frame, laterally-swinging wheel-carrying frames pivoted thereto, folding mechanism for swinging said frames to retract and project the wheels, a plurality of locking devices extending across the space between the wheel frames, and adapted to lock and release the latter, the locking devices being separate from the folding mechanism, and connections between the folding mechanism and the locking devices, whereby the latter are simultaneously actuated through the operation of the folding mechanism.

6. In a folding carriage, the combination of a seat frame, laterally-swinging wheel-carrying frames pivoted thereto, folding mechanism for swinging said frames to retract and project the wheels, a plurality of struts connecting the wheel frames, and adapted to be lengthened and shortened to lock and release the wheel frames, said struts being separate from the folding mechanism and connected for simultaneous operation, and connections between the folding mechanism and struts whereby the latter are simultaneously shortened and lengthened by the operation of the folding mechanism.

45 7. In a folding carriage, the combination of a seat frame, laterally-swinging wheel-carrying frames pivoted thereto, folding mechanism for swinging said frames to retract and project the wheels, a plurality of toggle struts connecting the wheel frames, each comprising a central link and two end links, jointed to the central link and to the wheel frames, a rod connecting the two central links, and connections between the said rod and the folding mechanism adapted to raise and depress the rod and the central links to break and extend the toggles when the folding mechanism is operated to retract and project the wheel frames.

60 8. In a folding carriage, the combination of a seat frame, laterally-swinging wheel frames pivoted thereto, the seat frame having outwardly-projecting stops to limit the outward swinging movement of the wheel frames, a device for locking the wheel frames

and holding the same in their projected position against said stops, folding mechanism for swinging said wheel frames, said stops and locking device being separate from the folding mechanism and connections between the folding mechanism and the locking device whereby the latter is automatically actuated through the operation of the folding mechanism.

9. In a folding carriage, the combination of a seat frame, laterally-swinging wheel frames pivoted thereto, a handle pivoted to the seat frame, and jointed connections pivotally connected to the handle and the wheel frames, adapted to impart swinging movements from the handle to the wheel frames.

10. In a folding carriage, the combination of a seat frame, laterally-swinging wheel frames pivoted thereto, a handle pivoted to the seat frame, U-shaped ears jointed to the wheel frames, and connecting rods jointed to said ears and to the handle, said ears and rods constituting double-jointed connections adapted to impart swinging movements from the handle to the wheel frames.

11. In a folding carriage, the combination of a seat frame, laterally-swinging wheel frames pivoted thereto, a handle pivoted to the seat frame, connections between the handle and the wheel frames adapted to impart swinging movements from the handle to the wheel frames, a device for locking and releasing the wheel frames, levers pivoted to the seat frame in advance of the handle, arms jointed to the handle and levers above the seat frame, and connections between the locking device and the said handle and arms whereby the locking device is automatically actuated by movements of the handle and arms.

12. In a folding carriage, the combination of a seat frame, laterally-swinging wheel frames pivoted thereto, a handle pivoted to the seat frame, connections between the handle and the wheel frames, adapted to impart swinging movements from the handle to the wheel frames, a device for locking and releasing the wheel frames, levers pivoted to the seat frame in advance of the handle, arms jointed to the handle and levers above the seat frame, a vertically movable cross bar having ears at its ends jointed to the handle, links jointed to the said ears and to the arms, the said cross bar being vertically movable by movements of the handle, levers and arms, and connections between the said cross bar and locking device whereby the latter is actuated by vertical movements of the cross bar.

13. In a folding carriage, the combination of a seat frame, laterally-swinging wheel frames pivoted thereto, a handle pivoted to the seat frame, connections between the handle and the wheel frames adapted to impart swinging movements from the handle to the

wheel frames, toggle struts connecting the wheel frames, a rod connecting said struts, levers pivoted to the seat frame in advance of the handle, arms jointed to the handle and 5 levers above the seat frame, a vertically movable cross bar having ears at its ends jointed to the handle, links jointed to the said ears and to the arms, the cross bar being vertically movable by movements of the handle, 10 levers and arms, a lifting lever jointed at one end to the seat frame, and engaged at the other end with the strut-connecting rod, and a link connecting said lifting lever with the cross bar.

15 14. In a folding carriage, the combination of a seat frame, a propelling handle pivoted to the rear portion of the seat frame, a dasher pivoted to the forward portion of the seat frame, and connections between the handle 20 and dasher whereby swinging movements are imparted from the handle to the dasher.

15 15. In a folding carriage, the combination of a seat frame, a propelling handle pivoted to the rear portion of the seat frame, a dasher pivoted to the forward portion of the seat 25 frame, and means for imparting swinging movements from the handle to the dasher, the movements of the dasher being opposite those of the handle.

30 16. In a folding carriage, the combination of a seat frame, a handle pivoted to the rear portion of the seat frame, levers pivoted to the seat frame in advance of the handle, a dasher pivoted to the front portion of the 35 seat frame, rods connecting the handle with the upper arms of the levers, and rods connecting the dasher with the lower arms of the levers, said rods and levers communicating from the handle to the dasher swinging 40 movements in directions opposite to the swinging movements of the handle.

17. In a folding carriage, the combination of a seat frame, a handle pivoted to the rear

portion of the seat frame, levers pivoted to the seat frame in advance of the handle, a 45 dasher pivoted to the front portion of the seat frame, rods connecting the handle with the upper arms of the levers, and a seat supported by said rods above the seat frame, and movable toward and from the seat 50 frame by movements of the handle, rods and levers.

18. In a folding carriage, the combination of a seat frame, a handle pivoted to the rear portion of the seat frame, levers pivoted to 55 the seat frame in advance of the handle, a dasher pivoted to the front portion of the seat frame, rods connecting the handle with the upper arms of the levers, rods connecting the dasher with the lower arms of the levers, 60 said rods and levers communicating from the handle to the dasher, swinging movements in directions opposite to the swinging movements of the handle, a seat supported by the rods which connect the handle and levers, 65 and a collapsible pocket attached to the seat and dasher, and having a bottom forming a foot rest.

19. In a folding carriage, the combination of a seat frame, laterally swinging wheel 70 carrying frames pivoted thereto, a jointed brace between said wheel carrying frames, and connections whereby the brace is automatically actuated by the folding and unfolding of the carriage. 75

20. In a folding carriage, the combination of a seat frame, a swinging dasher, and means to automatically swing the dasher to and from its operative position by the unfolding and folding of the carriage. 80

In testimony whereof I have affixed my signature, in presence of two witnesses.

ORA NORCROSS TURNER.
